UNITED STATES PATENT OFFICE.

JOSEPH I. PEYTON AND SAMUEL E. HITT, OF SYDNEY, NOVA SCOTIA, CANADA.

INGOT-MOLD.

1,139,219.

Specification of Letters Patent. Patented May 11, 1915.

Application filed August 22, 1914. Serial No. 858,078.

To all whom it may concern:

Be it known that we, JOSEPH I. PEYTON and SAMUEL E. HITT, citizens of the United States, residing at Sydney, in the county of 5 Cape Breton, Province of Nova Scotia, and Dominion of Canada, have invented certain new and useful Improvements in Ingot-Molds, of which the following is a specification.

10 Our invention relates to improvements in ingot molds, and it consists in the constructions, combinations, and arrangements herein described and claimed.

An object of our invention is to provide an 15 improved ingot mold adapted to minimize the defects due to pipes, blow holes, cavities, and segregation usually found in ingots.

A further object of our invention is to provide a strong and durable metallic ingot 20 mold formed with an interior vacuum chamber for efficiently retarding the radiation of heat from the upper portion of the cast ingot.

In the accompanying drawings: Figure 1 25 is a central, vertical section of an ingot mold, illustrating one embodiment of our invention; Fig. 2 is a section on the line $x-x$ of Fig. 1; Fig. 3 is an enlarged, detail section on the line $y-y$ of Fig. 2; Fig. 4 is a 30 view similar to Fig. 3, illustrating a modified construction; Fig. 5 is a detail section on the line $z-z$ of Fig. 4; Fig. 6 is a front view of the closure valve shown in Fig. 4, and Fig. 7 is a detail, front elevation of the 35 construction shown in Figs. 4 and 5 for protecting the valve.

Referring to the drawings, 1 indicates an open top ingot mold having a vacuum chamber 2 formed in its side walls and spaced 40 from the top thereof sufficiently to provide a relatively thick top wall to said chamber; the side walls of said mold being thickened to provide the vacuum chamber 2 with substantial, heavy outer and lower walls. This 45 provides an improved construction, in which the vacuum chamber 2 is provided with relatively thick upper and lower walls connecting the inner and outer walls of said chamber; thereby providing efficient means for 50 conducting heat from the top and bottom of said inner walls uniformly throughout said top and bottom portions. This improved construction insures a continuous and uniform conduction of heat from the inner walls 55 of the vacuum chamber 2; thereby preventing deterioration or destruction of the mold

by disadvantageously high heating of the inner walls of the vacuum chamber 2 from the hot cast metal in contact therewith, and avoiding injurious irregular or localized 60 cooling of said inner walls.

As shown in Fig. 3, an outlet 4 from the vacuum chamber 2 communicates with a pipe plug 5, which latter is secured to the mold and adapted to be connected to any suitable 65 device, such as an air pump, for exhausting the air from said vacuum chamber. The pipe plug 5 is shown with its walls pinched together and bent over at 6, to effectively seal the vacuum formed in the chamber 2; if 70 desired, the pipe plug may be heated to readiness to facilitate such sealing operation.

Figs. 4, 5, 6, and 7 illustrate an advantageous form of closure for sealing the vacuum formed in the chamber 2, which comprises a 75 short pipe 7 secured to the mold in communication with outlet 4 of the vacuum chamber, and provided with a valve 8 having a handle 9; a threaded nipple 16 being shown on said valve for convenient connection to 80 any suitable device for exhausting the air from said chamber 2.

Our improved construction provides a compact and strong means for protecting the 85 valve 8 from the slag or metal overflow, or from accidental opening, which consists of a projecting hood 10 and a shield 11 pivoted at 12 in ears beneath said hood. As shown especially in Fig. 4, the pivoted shield 11 90 extends over the valve 8, and is adapted to be clamped securely in closed position by a rod 14 inserted through perforated lugs 15 on the mold; said clamping rod 14 being shown locked in position by bending its ends down over said lugs 15. 95

The valve 8 is so positioned that its actuating handle 9 is confined against turning, from the closed position of said valve, by the adjacent faces of the shield 11 and mold 1; thereby preventing accidental shifting or 100 jarring of the valve to open position.

In the operation of our invention, the air is exhausted from the vacuum chamber 2, and the mold filled with molten metal to a level approximating the top of said chamber. During the cooling and solidification 105 of the cast metal in the mold, the heat imparted to the inner walls of the vacuum chamber by the hot metal in contact therewith will be gradually and uniformly conducted from said inner walls by the relatively thick top and bottom walls of said 110

chamber; thereby insuring an efficient and uniform insulating action of the vacuum chamber, and avoiding danger of injury to the inner walls of said chamber by excessively high heating thereof, or by irregular or localized cooling.

Our invention, thus, provides a strong and durable ingot mold in which the vacuum chamber constitutes a highly efficient heat-insulating means for materially retarding the cooling and solidification of the upper portion of the cast metal in the mold; thus minimizing the defects due to piping, blow holes, cavities, and segregation in the cast 10 ingot.

15 We have illustrated and described preferred and satisfactory constructions, but changes could be made within the spirit and scope of our invention.

20 We claim:

1. An open top ingot mold having a vacuum chamber formed in its side walls and spaced from the top of the mold to provide a relatively thick upper wall for such vacuum chamber.

2. An open top ingot mold having a vacuum chamber formed in its side walls and spaced from the top of the mold to provide a relatively thick upper wall for such vacuum chamber, the upper portion of the mold walls being thickened to provide heavy lower and outer walls for such vacuum chamber.

3. An open top ingot mold having a vacuum chamber in the upper portion of its side walls, a manually-operated closure secured to the outer face of the mold in communica-

tion with such vacuum chambers, and a protecting hood projecting from the mold above said closure.

4. An open top ingot mold having a vacuum chamber in the upper portion of its side walls, a manually-operated closure secured to the outer face of the mold in communication with such vacuum chamber, a protecting hood projecting from the mold above said closure, a shield pivoted beneath said hood for inclosing said closure, and means for clamping said shield in closed position.

5. An open top ingot mold having a vacuum chamber in the upper portion of its side walls, a closure for such vacuum chamber secured to the mold, an actuating handle for said closure, a shield for inclosing said closure and confining said actuating handle against shifting, and means for clamping said shield in closed position.

6. An open top ingot mold having a vacuum chamber in the upper portion of its side walls, a closure for such vacuum chamber secured to the outer face of the mold, a protecting hood projecting from the mold above said closure, an actuating handle for said closure, a shield pivoted beneath said hood for inclosing said closure and confining said handle against shifting, and means for clamping said shield in closed position.

In testimony whereof we affix our signatures in the presence of two witnesses.

JOS. I. PEYTON.
SAMUEL E. HITT.
